UNITED STATES PATENT OFFICE.

JOHN R. WINTER, OF DETROIT, MICHIGAN, ASSIGNOR TO KELSEY WHEEL COMPANY, OF DETROIT, MICHIGAN, A CORPORATION OF MICHIGAN.

METHOD OF FORMING WHEEL-HUBS.

1,257,569.

Specification of Letters Patent. Patented Feb. 26, 1918.

Application filed August 31, 1914. Serial No. 859,570.

To all whom it may concern:

Be it known that I, JOHN R. WINTER, a citizen of the United States of America, residing at Detroit, in the county of Wayne and State of Michigan, have invented certain new and useful Improvements in Methods of Forming Wheel-Hubs, of which the following is a specification, reference being had therein to the accompanying drawings.

10 The invention relates to methods of forming wheel hubs from sheet metal blanks, and has particular reference to the manner of forming a roll or return-bent connection between the cylindrical body of the hub and 15 the annular flange.

In the present state of the art wheel hubs have been formed from a flat blank by cupping to form the cylindrical body portion, leaving an annular flange in the original 20 plane of the blank for extending at one side of the spokes. When formed in this manner it is impossible to avoid a round fillet between the flange and the cylindrical body, which interferes with the butting of the 25 ends of the spokes against the cylindrical portion. Furthermore, to properly center the bearings in the hub it is desirable to have the cylindrical portion extended outside of the plane of the flange. Such a result can only be accomplished by forming a 30 return-bend intermediate of the cylindrical body and the flange, which structure is difficult to form by dies. I have therefore devised a novel method of forming a hub with 35 such a return-bend as hereinafter set forth.

In the drawings:

Figure 1 is a section through a blank after the cupping operation, for forming the cylindrical portion;

40 Fig. 2 shows the manner of initiating the return-bend;

Fig. 3 illustrates the operation for completing the return-bend;

Fig. 4 shows the bend after completion;

45 Fig. 5 is a complete central vertical sectional view of the parts positioned as partly shown in Fig. 2; and

Fig. 6 is a complete vertical section of the parts positioned as partly shown in Fig. 4.

50 The sheet metal blank is first fashioned by the usual cupping operations to form a structure having a cylindrical portion A, the outwardly-extending annular flange B at

the end thereof, and a flaring portion C intermediate the portions A and B. The blank 55 is then pressed in dies D and E, which re-fashion the flaring portion C to produce a slight return-bend F between the flange B and cylinder A. This operation may be readily performed, as the opening is so 60 slight as not to require any considerable flow of the metal or change in the gage thereof. If, however, a deep return-bend is to be formed by die operations, this would necessitate a succession of steps, in each of which 65 the return-bend would be but slightly increased in depth. I have greatly simplified the process by subjecting the blank with the initial return-bend therein to the action of a hammer which in a single blow completes 70 the formation of the structure desired. Thus, as shown in Fig. 3, the portion A of the blank is held in a die G with the flange B and initial return-bend F spaced from the upper surface H of said die. A drop or 75 hammer die I, having an annular portion J and recess K, is then caused to operate against the flange B, carrying this downward against the surface H, and rolling over the metal intermediate of the flange and the 80 cylindrical portion of the blank to form the top return-bend K. During this operation the metal which is return-bent is free to flow in its natural course and to distribute itself without restraint. Thus, as shown in Fig. 4, 85 the section is thickened at K' and the inside face of the bend is not parallel with the outer face thereof.

As has been stated, my improved process cuts out a number of steps necessary in die 90 operations, and consequently the cost of manufacture is reduced.

What I claim as my invention is:—

1. The method of forming flanged wheel hubs, comprising the drawing of a flat blank 95 to form a cylindrical portion with an annular flange at one end, re-fashioning the metal intermediate of said flange and cylindrical portion to initiate a return-bend, and carrying said flange backward over said cylindrical portion to roll over and deepen said return-bend.

2. The method of forming flanged wheel hubs, comprising the drawing of a flat blank 100 to form a cylindrical portion with an annular flange at one end thereof, re-fashioning 105

the metal intermediate of said flange and cylindrical portion to initiate a return-bend, and subjecting said flange to a hammer blow to carry the same over said cylindrical portion and to roll over and deepen said return-bend.

3. The method of forming flanged wheel hubs, comprising the drawing of a flat blank to form a cylindrical portion with an annular flange at one end and a flaring intermediate portion, re-fashioning said flaring intermediate portion to initiate a rounded return-bend, engaging said cylindrical portion in a fixed relation to a die or anvil with said flange spaced from said die or anvil, and subjecting said flange to a hammer blow for flattening the same against said die or

anvil and for rolling over and deepening said return-bend.

4. The method of forming flanged wheel hubs, comprising the drawing of a flat blank to form a cylindrical portion with an annular flange at one end, and carrying said flange backward over said cylindrical portion and simultaneously rolling the portion of the cylinder adjoining the flange to form a return-bend. 20 25

In testimony whereof I affix my signature in presence of two witnesses.

JOHN R. WINTER.
